COMBINED BATTERY OPERATED DENTAL APPLIANCE AND RECHARGING RACK

John B. Fattaleh, 4845 E. Indian School Road,
Phoenix, Ariz. 85018

Filed July 26, 1974, Ser. No. 492,199

Term of patent 14 years

Int. Cl. D24—02

U.S. Cl. D24—1

FIG. 1

FIG. 3

FIG. 4

FIG. 5

FIG. 6

FIG. 7

FIG. 8

FIG. 9

FIG. 10

FIG. 1 is a perspective view of the front and top of a combined battery operated dental appliance and recharging rack showing my new design;

FIG. 2 is a right and rear and bottom perspective view of the recharging rack with a partial end view of the dental appliance;

FIG. 3 is a top perspective view of the dental appliance;

FIG. 4 is a left end view of the dental appliance;

FIG. 5 is a right end view of the dental appliance;

FIG. 6 is an elevational view of the bottom of the dental appliance;

FIG. 7 is a top plan view of the recharging rack with the dental appliance removed;

FIG. 8 is a front elevational view of the recharging rack with the dental appliance removed;

FIG. 9 is a left side elevational view of the recharging rack; and

FIG. 10 is a right side elevational view of the recharging rack.

I claim:

The ornamental design for a combined battery operated dental appliance and recharging rack, as shown and described.
